UNITED STATES PATENT OFFICE.

JOSEPH RIDDELL, BERT H. PATTERSON, WILLIAM DEVLIN, AND ARCHIBALD SMITH, OF SHARON, PENNSYLVANIA.

VALVE FOR REGENERATIVE FURNACES.

SPECIFICATION forming part of Letters Patent No. 684,102, dated October 8, 1901.

Application filed February 12, 1901. Serial No. 47,065. (No model.)

To all whom it may concern:

Be it known that we, JOSEPH RIDDELL, BERT H. PATTERSON, WILLIAM DEVLIN, and ARCHIBALD SMITH, citizens of the United States, residing at Sharon, in the county of Mercer and State of Pennsylvania, have invented certain new and useful Improvements in Valves for Regenerative Furnaces, of which the following is a specification.

10 Our invention relates to improvements in valves for regenerative and like furnaces and means for operating the said valves. We have aimed to provide a construction of valve in which a perfectly-tight joint will be effected without resorting to a liquid seal, thus avoiding the disadvantageous effects due to the contact of the gases with the liquid. We have also aimed to improve the details of the valve, whereby the ill effects due to expansion and 15 contraction are avoided, and we have also provided an improved means for operating the valves capable of being easily and accurately adjusted to insure the proper seating of the valves.

20 With these objects in view the invention comprises the details of construction hereinafter described and particularly pointed out in the claims.

The invention is illustrated in the accompanying drawings, in which—

Figure 1 is a central vertical section through the valve-chambers and valves. Fig. 2 is an enlarged detail view of one of the posts. Fig. 3 is a side elevation of the valve-operating wheel.

Referring to the first figure, the numerals 11 are valve-chambers, the walls of which are formed of any suitable material, such as wrought iron or steel, and are each provided 25 internally with upper and lower seats 23, arranged to coact with the double-faced vertically-movable valves 44. The chambers are connected above by a passage or chamber 5, which communicates by an opening 6 with the usual gas-main (not shown) controlled 30 by a mushroom-valve 7. The openings through the lower valve-seats communicate with the chimney, and the lateral openings 8 communicate by suitable flues with the regenerator in the manner well understood by those skilled in the art. Each valve 4, it will be

observed, comprises a circular hollow casting having upper and lower beveled edges co-operating with the upper and lower valve-seats. A hollow valve-stem 9 has its lower 35 threaded end screwed through the valve, and clamp-nuts 10 11 are screwed upon said tubular stem above and below the valve and serve to reinforce the connection and secure the valve effectively to the stem. A plurality of 40 openings connect the interior of the stem with the inside of the valve. Within the tubular stem 9 is a pipe 12 of such a size as to provide an annular space between the valve and stem, and at the top said stem and pipe are 45 suitably connected by a head or casting 13, through which are passed suitable feed and return pipes 13' for connecting a source of water-supply with the pipe 12 and the annular space, whereby a flow of water through 50 the valve and the effectual cooling thereof are insured. The nut 11, it will be seen, forms a cap, which closes the end of the valve-stem and may be readily removed for cleaning 55 purposes. In order to move the valves alternately, we provide a pulley-wheel 15, (shown in Fig. 3,) over which a cable 16 passes, which is connected with suitable eyes in the upper end of the valve-stems.

Two arms 17 and 18 are secured to the 60 wheel and project radially therefrom, one of these terminating in a handle 18^a. A post 19 is arranged on each side of the wheel, designed to support a cam-operated abutment 20. We prefer to mount the abutment in the following manner: A rod 21 has its lower portion threaded and screwed into the upper end of the post 19, and by means of the threaded connection it may be adjusted to any extent desired and locked into position by a lock-nut 22. The abutment 20 referred to is carried by or forms a part of a collar 23, which has a splined connection with said rod 21 and is freely movable vertically thereof, being normally forced upward by a helical spring 24, the tension of which may be varied by means of the nut 25. A rotatable collar 26 encircles the rod 21 above the collar 23 and has upper and lower inclined faces 26^a, which correspond to and coact with similar inclines 100 on the collar 23 and a stationary collar 27 on the other end of the rod. A handle is pro-

vided for rotating the collar 26. It will thus be seen that when the wheel 15 is rotated to reverse the valves one of the arms 17 or 18 comes beneath the abutment 20 and is engaged thereby, as shown to the right of Fig. 3. A rotation of the cam 26 forces the collar 23, with its abutment 20, downward, thereby applying powerful pressure to the arm and effecting a tight joint of the valve which has 10 been drawn upwardly. By the threaded arrangement of the parts described the height of the abutment may be very accurately adjusted.

In order that the arms may be readily disengaged from the abutments, they are made of sufficient flexibility to allow them to be sprung laterally to carry the engaging portions from under the abutments, while being perfectly rigid under strains exerted circumferentially of the wheel by reason of the metal being set edgewise.

Having thus described our invention, what we claim is—

1. A valve for regenerative and like furnaces comprising a valve chamber or casing having internal upper and lower seats, a hollow valve-disk having faces for coöperating with said seats, a tubular valve-stem screwed completely through said disk, a nut or cap 25 closing the lower end of said tube, said tube having openings communicating with the interior of the valve, and water-circulating pipes coöperating with said tubular stem, substantially as described.
2. A valve for regenerative and like furnaces, comprising a valve-casing having upper and lower internal valve-seats, a hollow valve arranged to coöperate therewith, a tubular valve-stem screwed completely through 30 said valve and having openings communicating with the bottom portion of the valve, a cap or nut closing the lower end of the stem and abutting against the lower side of the valve, a second nut screwed upon said tube 35

and abutting against the upper side, a pipe 45 within and of less diameter than said tube and forming an annular space, and water flow and return pipes connecting with said pipe and said annular space, substantially as described.

3. In a regenerative or like furnace, the combination with the two alternately-operating valves, of a hand-wheel or pulley, a cable connected with the valves and passing over said pulley, and means for applying extra 55 pressure to said hand-wheel at each extremity of its movement to effect a tight closing of the valves, substantially as described.

4. In combination, the alternately-operating valves, a pulley-wheel, a cable passing 60 over the same and connected to the valves, arms carried by said wheel, movable abutments adapted to engage said arms at the extremities of the movement of the wheel, and cams journaled in proximity to said abutments for moving the same, substantially as described.

5. In combination with the alternately-operating valves, a pulley-wheel, a cable passing around the same and connected to the 70 valves, a pair of arms radiating from the pulley, pulley-wheel posts located on opposite sides of the pulley-wheel, abutments carried by the pulley-posts for engaging the arms, springs bearing on said abutments and cams 75 located in proximity to the abutments for depressing said abutments, substantially as described.

In testimony whereof we affix our signatures in presence of two witnesses.

JOSEPH RIDDELL.
BERT H. PATTERSON.
